CASING FOR HOUSING A HEARING AID AMPLIFIER, MICROPHONE, AND BATTERY, OR SIMILAR ARTICLE

Byron R. Criswell, Waukegan, Ill., assignor to Zenith Radio Corporation, a corporation of Delaware

Application March 14, 1957, Serial No. 45,258

Term of patent 14 years

(Cl. D26—14)

Fig. 1

Fig. 2

Figure 1 is a side elevational view of a casing for housing a hearing aid amplifier, microphone and battery, or similar article, showing my new design, the opposite side being substantially a mirror image thereof; and

Figure 2 is a top plan view thereof.

The dominant features of my design reside in those portions shown by means of full lines in the drawing.

I claim:

The ornamental design for a casing for housing a hearing aid amplifier, microphone and battery, or similar article, as shown and described.
